UNITED STATES PATENT OFFICE.

CARL P. NACHOD, OF PHILADELPHIA, PENNSYLVANIA.

ELECTRIC SIGNALING SYSTEM.

1,108,927.

Specification of Letters Patent.

Patented Sept. 1, 1914.

Application filed February 25, 1910. Serial No. 545,869.

To all whom it may concern:

Be it known that I, CARL P. NACHOD, a citizen of the United States, residing in the city of Philadelphia, county of Philadelphia, 5 and State of Pennsylvania, have invented a new and useful Electric Signaling System, of which the following is a specification.

My invention relates to a system of signaling used in connection with car or train movements of railways, and particularly to the car or train movements of a railway system using electrical energy for its motive power, and more particularly to such electric railways as have single track sections 15 or blocks with turn-outs at various intervals for the passage of cars moving in opposite directions, or to such railways as are for the major part double tracked, and have one or more single track sections.

20 My present invention resides in a system of and apparatus for electric signaling in which the signals are set or cleared according to the direction of the train or car running past the point where signal controlling means, such as insulated rail sections or contact device, is located, the preferred form of contact device being a trolley switch having no moving parts.

My invention resides further in a system 30 and apparatus, in which means are provided to insure that the signals, actuated or controlled by the directional trolley switch, shall be left in the same condition, after a car has improperly run into a block against a danger 35 or prohibitive signal and backed out again to wait, as before it so improperly ran into the block.

My invention resides in other features hereinafter described and claimed.

40 For an illustration of some of the many forms my invention may take, reference is to be had to the accompanying drawings, in which:

Figure 1 is a diagrammatic view of my improved signaling system and apparatus showing the circuits and controls in normal condition, that is with no signals displayed, and illustrates my invention as applied to a car counting system. Fig. 2 is a simplified 45 diagrammatic view of a modification of the apparatus and system shown in Fig. 1. Fig. 3 is a simplified diagrammatic view of a further modification or form my invention may take. Fig. 4 is a simplified diagrammatic 50 view of still another modification or form my invention may take. Fig. 5 is a simplified

55 fied diagrammatic view of a further modification or form my invention may take. Fig. 6 is a simplified diagrammatic view of a further modification or form my invention may take. Fig. 7 is a side elevational view of a semaphore controlling or operating means with attached semaphore switch. Fig. 8 is an end elevational view of the apparatus shown in Fig. 7. Fig. 9 is a diagrammatic view illustrating a trolley switch associated with each branch of a turn-out. Fig. 10 is a diagrammatic view illustrating the momentary engagement of successive trolley switch contacts by the moving trolley 70 wheel or other moving contact.

Referring to Fig. 1, I have shown my invention applied, by way of example, to a car counting system, such as disclosed in my prior application Serial No. 457,520.

75 In Fig. 1, 1 represents the trolley or contact feeder wire or conductor of an electric railway system for a single track block or section which may be of considerable length, but here shown as relatively short. At either end of the block or section 80 1 are turn-outs or side tracks to allow cars going in opposite directions to pass each other, or double tracked sections, there being a signal station A at the turn-out or 85 double track at the left and a similar signal station B at the turn-out or double track at the right, the trolley or contact conductor being branched at station A into the double track or turn-out or branch conductors 2 and 3, while at station B the single track conductor 1 branches into the double track or turn-out or branch conductors 4 and 5. In the block 1 traffic is in both directions, 90 while in the tracks corresponding with conductors 2 and 4 traffic is toward the left, and over the tracks associated with conductors 3 and 5, the traffic is toward the right, all as indicated by the arrows. At each end of the block 1 approximate a turn-out there is 95 provided a trolley switch which may assume a desirable form or construction so long as it has neighboring contacts 6 and 7.

The trolley switch may take the form disclosed in my prior Patent No. 922,024, 100 granted May 18, 1909. In such case one of the longitudinally extending contact strips, as q of said prior patent, may be divided into two parts insulated from each other, so that the trolley wheel or other moving 105 contact will first engage one part of such divided strip and immediately thereafter

engage the other part, such parts being represented as the contacts 6 and 7 in Fig. 1 of my present application. The contact 8 of Fig. 1 may take the place of the strip 5 of my said prior patent and may, as in that case, be permanently electrically connected to the trolley or other contact conductor 1.

The contact 6 at each station is connected 10 by conductor 9 with the light armature 10 of a relay or electro-magnet 11, the armature 10 being held by gravity or a light spring against a contact 12 and adapted when the magnet or relay 11 is energized 15 to be attracted into engagement with contact 13, one terminal of the winding of the magnet 11 being connected to said contact 13 and the other terminal connecting through the resistance 14 with the earth 20 or return conductor 15. Similarly, the trolley switch contact 7 connects by a conductor 16 to the light armature 17 of the electro-magnet or relay 18, said armature 17 being normally held by gravity or a light spring 25 in engagement with contact 19 and when the magnet or relay 18 is energized is adapted to engage with contact 20. One terminal of the winding of the magnet or relay 18 connects with the contact 20 and 30 the other terminal connects through the resistance 21 with the earth or return conductor 15. The contacts 13 and 19 are connected together by conductor 22, and contacts 12 and 20 are connected together by 35 conductor 23.

The conductor 24 connects with the contact 13 and with one terminal of the electro-magnet F whose other terminal connects through resistances r and r' with the earth 40 or return conductor 15. And the conductor 25 connects the contact 20 with the brush or contact 26 normally in contact with the bridging contact or ring 27 carried by but insulated from the movable core or armature 28 of the electro-magnet E, a second brush 29 also normally engaging the contact or ring 27 and connected by conductor 30 to one terminal of the winding of the electro-magnet C whose other terminal connects by conductor 31 through resistances r and r' to earth or return conductor 15.

The electro-magnet C has the movable armature or core member 32 normally held in unattracted position by the spring 33. 55 The core or armature 32 has attached thereto a rod 34 connected to the member 35 which, in the position shown in Fig. 1, abuts against the member 36 carried by the armature or core 37 of the electro-magnet 60 D, such core 37 being held normally in the unattracted position by spring 38. The rod 39, connected to the core or armature member 37, is notched at 40 to receive the latch or lock 41 actuated by a spring, not 65 shown, when the no-voltage magnet 42 is

deenergized, so that the core 37 and attached and controlled parts are held in the same position upon failure of energy in the line as they occupied before such failure of energy, the winding of the magnet 42 70 being connected preferably permanently between the trolley conductor 1 or 3, by a conductor 43, and the earth or return conductor 15 through a preferably employed resistance 44. 75

On the shaft 45 is mounted a toothed wheel 46 adapted to be stepped around in opposite directions by the pawls 47 and 48, spring controlled and pivoted respectively upon the members 35 and 36 of the opposing magnets C and D. Upon the shaft 45 is mounted also a contact wheel or disk 49 carrying the conducting pin 50 in electrical communication with said disk 49, and also carrying the insulating block or member 51. When the parts are in the normal position as shown in Fig. 1 the contact or brush 52 is in electrical communication with the pin 50 such brush 52 being connected by a conductor 53 with one terminal of the red signal lamp R, whose other terminal connects by conductor 53a with one terminal of the magnet E, so that the lamp R is connected, by conductors 53a and 53, 54, in multiple with the winding of the magnet E. The brush 52 connects also by conductor 54 with one terminal of the winding of the electro-magnet E, whose other terminal connects by a conductor 55 through a preferably employed resistance 56 with 10 the earth or return conductor 15. The brush or contact 57 bears normally upon the insulation 51 and is connected by conductor 58 with one terminal of the electro-magnet D whose other terminal connects by conductor 59 with the trolley or feed conductor as 1 or 3. The brush 57 connects also by conductor 60 with the brush or contact 61 bearing normally upon the bridging contact or ring 62 carried by but insulated from 11 the core or armature member 32 of the magnet C. The second brush or contact 63 also normally bears upon the contact 62 and connects by conductor 64 with a brush or contact 65 opposed to the brush 12 or contact 66 connecting by conductor 67 with one terminal of the white signal lamp W whose other terminal is connected to the trolley or contact conductor as 1 or 3. The brushes 65 and 66 are adapted to be 13 bridged by the ring or bridging contact 68 carried by but insulated from the rod 39 attached to the core or armature member 37 of the magnet D when said armature member 37 is moved toward the right as viewed in Fig. 1.

In continuous contact with the disk 49 is the brush 69 which connects by conductor 70 with the brush or contact 71 normally in engagement with the bridging contact or 14

ring 72 carried by but insulated from the movable armature or core member 73 of the electro-magnet F. The opposing brush 74 also normally engages the contact ring 72 and is connected by conductor 75, through a manual switch 76 at the distant or other station to the similar brush or contact 74.

The electro-magnets C, D, E and F are such, for example, as similarly characterized in my application Serial No. 457,520 and are interrelated with each other and with the step-by-step mechanism as disclosed in said application, except that herein the apparatus is sensitive to direction of movement of car or train under the same contact switch by means of the trolley switch and relays 11 and 18 as shown, together with the connections by conductors 24 and 25. As in my said prior application the resistance r associated with conductor 31 and winding of magnet C is normally short circuited by the brushes 77 and 78 bridged by the contact 79 insulated from but movable with the core member 32. Upon energization of the magnet C the contact 79 is removed from engagement with brushes 77 and 78 and the additional resistance r is thrown into circuit with the resistance r' in series with the magnet C. In like fashion, the resistance 56 associated with magnet E is normally short circuited by similar brushes 77 and 78 normally bridged by a ring or contact 79 and the operation is the same. And so also in the case of magnet F the resistance r is normally short circuited by its brushes 77 and 78 normally bridged by the ring or contact 79.

Connected to the conductor 25 by conductor 80 are the two contacts 81 and 82. Associated with the contact 81 is the contact 83 connected to conductor 84 to which also is connected the contact 85 associated with the contact 82.

The contacts 81 and 83 are adapted to be bridged by the contact 86 carried by but insulated from the arm 87 pivoted at 88 and carrying at its other end the red semaphore disk or blade 89. And similarly the contacts 82 and 85 are adapted to be bridged by the contact 90 carried by but insulated from the bar or rod 91 pivoted at 92 and carrying at its other end the white semaphore disk or blade 93. The semaphores 89 and 93 are similarly actuated and controlled. For simplicity, the mechanism of the semaphore 93 only is described, and illustrated in Figs. 7 and 8. Attached to the semaphore arm 91 is a weight 94 tending to move the semaphore 93 about its pivotal axis 92 in a clockwise direction, as viewed in Fig. 7, to indicating or display position. Normally, however, the rod 95 presses against the under side of the weight 94 to keep the same elevated and to keep the same in the position shown in Fig. 7. At the lower end of the

rod 95 is pivoted the bell crank lever 96 whose second arm is shown at 97, the bell crank being pivoted at 98. The rod 39 attached to the movable armature or core 37 of the magnet D engages the bell crank arm 70 97, the spring 38 holding the parts in the position shown, that is to say, holding the rod 95 elevated and holding the weight 94 raised. When the armature or core member 37 is moved to the right, as by the effect of magnet C, as hereinafter described, the rod 95 is moved downwardly so that the weight 94 is free to lift the semaphore to indicating or display position, and in that case the contact 90 is brought to position to bridge contacts 82 and 85. The other semaphore 89 is similarly controlled by the magnet E. And when in the indicating or display position causes the contact 86 to engage and bridge contacts 81 and 83.

The conductors required for the signaling system and apparatus as above described, are the conductors 75 and 84 extending from the one station or turn-out to the other.

The operation is as follows: When a car or train passes toward the right from the turn-out or station A to the single track block or section, the trolley or other moving or sliding contact will cause electrical communication to be established between the trolley or other feeder conductor 1 and the contact 6 of the trolley switch. Current then flows from conductor 1 through contact 6, conductor 9, through relay armature 10, contact 12, conductor 23, conductor 25, brush 26, ring or bridging contact 27, brush 29, conductor 30, the winding of the electro-magnet C, thence by conductor 31, brush 77, bridging contact 79, brush 78, resistance r' , conductor 31 to the ground or return track or return conductor 15, of the electric railway system. Current also passes from conductor 23 through the winding of the relay 18, resistance 21, to the ground or other return conductor 15, energizing said relay 18 and causing its armature to engage contact 20. As the trolley wheel or other moving contact proceeds from left to right, it engages contact 7 before leaving contact 6, so that for an instant contacts 6 and 7 are electrically connected. This is illustrated in Fig. 10, where the trolley wheel or moving contact w is shown leaving contact 6 and engaging contact 7 but in contact with both. The relay 18 having been energized due to the engagement with contact 6, it remains energized during the time the trolley wheel or other moving contact bridges contacts 6 and 7 and also during the time the trolley wheel or other contact is passing over the switch contact 7. Current then continues to flow from trolley or other conductor 1 through contact 7, conductor 16, relay armature 17, contact 20 and the winding of the relay 18 130

5 maintaining the same energized until the trolley wheel passes off to the right from contact 7. During this time, however, current also flows from contact 20 through conductor 25, and through the winding of the electro-magnet C as above described. During the traverse of contacts 6 and 7 by the trolley wheel, current flows through the conductor 25 and so continues to flow until 10 the trolley wheel has moved off from contact 7. And during this traverse of contacts 6 and 7 only one of the relays, namely, 18 is energized.

When current has passed, as above described, through the winding of the electro-magnet C, the same is energized and its core or armature member 32 is attracted toward the right, as viewed in Fig. 1. During this movement the bridging contact 79 separates from brushes 77 and 78 and there is in effect cut into the circuit of the winding of the magnet C the extra resistance section r which reduces the current, which is now, however, sufficient to maintain the armature or core in its attracted position, and the current being thus reduced the heating of the magnet C is reduced. As the core member 32 is attracted toward the right it operates the pawl 47 to step the toothed wheel 46 around one notch and it simultaneously pushes toward the right the armature or core member 37 of the electro-magnet D, thus causing the rod 95, Figs. 7 and 8, to be removed from beneath the weight 94, allowing such weight then to move the white semaphore or disk 93 in a clockwise direction, as viewed in Fig. 7, to bring the same to display position. When the parts have reached this position the contact disk 49, mounted on the same shaft 45 with the notched wheel 46, has been rotated so as to remove the insulation 51 from beneath the brush 57, thus bringing brush 57 into engagement with the contact wheel 49 and, in effect, bringing brushes 57 and 69 into electrical communication with each other. Simultaneously, however, the contact pin 50 has been removed from beneath the brush 52. Current may now flow from trolley or feed conductor 1 or 3 through conductor 59, through the winding of the electro-magnet D, maintaining the same energized, brush 57, disk 49, brush 69, conductor 70, through brush 71, bridging contact 72, brush 74, thence through manual switch 76 to conductor 75 which extends to the distant station B where current passes through the switch 76, thence by conductor 75 through brush 74, bridging contact 72, brush 71, conductor 70 to brush 69, thence through the disk 49, through pin 50, brush 52, conductor 54, winding of the electro-magnet E, conductor 55, thence through brush 77, bridging contact 79, and brush 78, associated with magnet E, to earth or return con-

ductor 15. When the electro-magnet E is thus energized it allows the red disk or semaphore at station B to move to indicating position by a control such as shown in Fig. 7. Here again when the movable core or armature of the magnet E is attracted toward the left, as viewed in Fig. 1, the contact 79 separates from brushes 77 and 78, thus throwing into circuit with the winding of the magnet E a resistance 56, which reduces the current, which is, however, sufficient to hold the parts in the attracted position.

Simultaneously with the energization of the magnet E at the distant station B the red signal lamp R burns since it is connected in multiple or parallel with the winding of the electro-magnet E. Then we have the state of affairs that the magnet D continues energized but the magnet C has been deenergized. Current may then flow from the trolley or feed conductor 1 or 3 through the white incandescent signal lamp W, conductor 67, brush 66, bridging contact 68, which has now been moved to the right because magnet D is energized, brush 65, conductor 64, brush 63, bridging contact 62, brush 61, conductor 60, to brush 57, which is now in engagement with the disk 49, through brush 69, conductor 70, through the line signal wire 75, through the apparatus at the other station, to the earth or return conductor 15. White light W is thus operated in shunt with magnet D. We have then at station A the white light burning, and the white disk or semaphore displayed, while at the distant station the red light and red disk or semaphore are displayed for a car or train entering the block at station A and moving toward the right, in Fig. 1. With the white semaphore in indicating position at station A, the semaphore switch 82, 85, at station A is closed; and since at station B the red semaphore is in indicating position, the red semaphore switch 81, 83 at station B is closed. Although the above mentioned semaphore switches are closed, a car entering from the left at station A and bringing the trolley wheel into engagement with contact 6 can produce no effect in the distant apparatus at station B, since at station B the switch 26, 27, 29 is opened immediately upon the energization of the magnet E at station B and before the red semaphore switch 81, 83 at station B closes. And so on for each successive car or train passing under the trolley switch, the wheel 46 is stepped around a notch and the white light W is temporarily extinguished, but there is no change at the distant station where the signals show red or danger against any train or car attempting to enter toward the left into the block from station B.

As each car or train moves out to the 1

right from the block or section to the turnout at station B, the trolley wheel or other moving contact first engages trolley contact 7, whereupon current flows from the trolley 5 conductor through conductor 16, armature 17, contact 19, conductor 22, through the winding of relay 11, at station B, to earth, energizing said relay and causing its armature 10 to be attracted against contact 13. 10 Current also flows during the traverse of contact 7 by the trolley wheel through conductor 22, conductor 24, thence through the winding of the electro-magnet F at station B to earth or return conductor 15, energizing such electro-magnet F and causing it to withdraw the bridging contact or ring 72 15 from between the brushes 71 and 74, thus interrupting the current in the signal wire 75 and thus causing deenergization of magnet D at station A, whereupon the spring 38 causes the notched wheel 46 to be stepped backward toward normal one notch. Then for an instant the trolley wheel bridges trolley switch contacts 7 and 6 and then 20 traverses the contact 6. And during all this time current continues to flow through the conductor 24 and during all this time of traverse of both contacts 7 and 6 the electro-magnet D at station A is deenergized. When 25 the trolley wheel has passed off contact 6 at station B the magnet F is deenergized and the circuit is again closed between brushes 71 and 74. And if it be the last car or train which has passed off from block 30 1 to the turn-out at B, the parts at station A have returned to normal position with the brush 57 resting upon the insulation 51. It is apparent, therefore, that when all cars have passed out of the block section 1 to 35 the turn-out B all the signals and apparatus are returned to normal position.

The relays 11 and 18 are quick-acting relays and their moving parts, as their armatures, are preferably made very light and 40 of very small inertia so that they may be quickly attracted. These relays 11 and 18 operate so quickly that before the first trolley switch contact has been traversed the controlled relay armature has been fully 45 attracted. These reversing relays 11 and 18, in combination with the trolley switch having a divided contact, as 6, 7, are so connected with the trolley switch that whichever end or contact of the switch is first 50 reached by the trolley wheel, the relay will cause the other contact of the trolley switch to be connected with the same magnet or device in the main signaling apparatus. By 55 this means the full length of the contacts in the trolley switch is utilized for electrical contact. And it is apparent also that by the reversing relays current is permitted to pass over either one of two conductors, as 60 24 and 25, current being allowed to pass 65 over one conductor when the trolley wheel

passes over the trolley switch in one direction, and over the other conductor when the trolley wheel passes over the trolley switch in the other direction.

Suppose that one or more cars or trains 70 has or have entered from the right toward the left from station B to the block or section. Then, at station B the notched wheel 46 has been stepped around as many notches as cars or trains have entered the block or section, and the white light and white semaphore are displayed at station B and the white semaphore switch 82, 85 is closed; and at station A the red light and red semaphore 75 are displayed and the red semaphore switch 81, 83 at station A is closed. And suppose a car or train improperly runs past the red signal at station A from the turnout to the block section under the trolley switch 6, 7 at station A. The trolley wheel 80 first engages contact 6, with the result that current will flow through conductor 9, relay armature 10, contact 12, conductor 23, through winding of relay 18, energizing the 85 same and causing its armature 17 to engage contact 20; and current also flows from conductor 23 through conductor 25. But current from conductor 25 cannot pass through brush 26 to brush 29, at electro-magnet E of station A, because the red semaphore 90 magnet E at station A is energized, with the result that the bridging contact 27 has been withdrawn from between brushes 26 and 29, and, accordingly, the magnet C at station A 95 cannot be energized. Current does, however, flow from conductor 25 through conductor 80, through red semaphore switch 81, 83 at station A, over the second signal wire 84 to the station B, thence through the white semaphore switch 82, 85 at station B, 100 then by conductor 80 through the bridged brushes 26 and 29 and through the winding of the magnet C at station B, causing magnet C to be energized and thereby step 105 around the notched wheel 46 one more notch, just as if one more train or car had entered the block toward the left from station B. 110

When a car or train which has improperly entered the block from a station A toward the right, causing the operation just above 115 described, backs out again, the trolley should not be removed from the trolley wire, but the car should back out past the trolley switch 7, 6 at station A, the trolley wheel first engaging trolley switch contact 7. 120 When the contact 7 is so engaged by the returning trolley wheel, relay 11 at station A is energized and current will also flow over conductor 24 through the winding of the electro-magnet F to earth at station A causing 125 the energization of the magnet F and the consequent interruption of circuit between brushes 71 and 74, thereby breaking the current in the signal wire 75 and causing the deenergization of magnet D at station 130

tion B, with the result that the notched wheel 46 at that station is now returned one notch toward normal, thus canceling at station B the effect upon the notched wheel 46 of the improper entry of a car or train from station B to the block against the previously set red signal. This improper running past the red or danger signal at a station is quite likely to occur without any fault on the part of the signal system or apparatus or on the part of the operator or motorman upon the car, because, for example, a car or train may reach the trolley switch 6 in passing toward the left from station B to the block, just a moment before a car passes from station A to the block toward the right. The result is that instantly the red signal is displayed at station A, and yet the car at station A cannot be stopped quickly enough to prevent the actual running past the trolley switch. When the motorman or operator has then brought his car to a stop, he backs off, as above described, canceling the effect in the signaling apparatus at the distant station.

The second signal wire 84 with its co-operating parts causes the counting up on the notched wheel at a distant station one notch for every car which has improperly passed the red signal at the home station; while the cancellation of this counting up at the distant station is secured by interrupting the current in the signal wire 75. Thus, the signal wire 84 with its co-operating parts is a means for producing an operation in the signaling apparatus at a distant station corresponding with the entry at that distant station to the block of a car or train. The signal wire 84 with its co-operating parts in effect puts the signal apparatus at the distant station in such condition that the subsequent backing out at the home station of a car or train, which has improperly entered the block against the red, will leave the signal apparatus at the distant station in its previous condition. It will appear, therefore, that the signal wire 84, with its associated semaphore switches, is a means of communication with the signaling apparatus at the distant station only, such that a record may be there produced for the improper entry of a car against the red at the home station, which record may be canceled through other means at the subsequent backing out of the car at the home station.

While I have shown the trolley switches as located on the single track, block or section, it is to be understood that they also may be located on each branch of the turn-outs, in which case similar trolley switch contacts are connected together, as seen in Fig. 9.

In Fig. 2 I have shown a modified arrangement of the signaling circuits accomplishing results similar to those described in connection with Fig. 1. Here, similar

reference characters refer to like parts in Fig. 1. Associated with the movable armature or core of the magnet E, however, is a further switch comprising the ring or bridging contact 99 and associated brushes 100 and 101, the brush 100 being connected with conductor 25. From the brush 101 at the left hand station A extends a conductor 102 to the conductor 25 at the right hand station. And from the brush 101 at the right hand station B extends a conductor 103 to the conductor 25 at the left hand station A, there being, accordingly, three signal wires extending between stations, namely, 75, 102 and 103. In this case there are no semaphore switches as in Fig. 1.

In counting in and counting out cars the operation of the arrangement shown in Fig. 2 is the same as that shown in Fig. 1. Suppose, however, that one or more cars or trains has or have entered the block or section from station B toward the left. The step-by-step mechanism at station B then has been moved as many notches as cars or trains have entered the block. Accordingly, at station B the white semaphore and white light are displayed, while at station A the red semaphore and red light are displayed, the magnet E being in such case energized at station A, with the result that bridging contact 27 has been removed from between brushes 26 and 29, while the ring or contact 99 has been brought into position to bridge brushes 100 and 101. Accordingly, when a car passes from the turn-out at station A toward the right to the block or section 1, trolley switch contact 6 is first engaged by the trolley wheel allowing current to flow from the trolley wire 1 through the contact 6, conductor 9, to the armature 10 of the relay 11, thence through contact 12, through conductor 23, thence through the winding of the relay 18, to earth or return conductor 15, energizing said relay to bring its armature 17 into engagement with the contact 20. Current also flows from conductor 23 through conductor 25, thence through brush 100, bridging contact 99, to brush 101, and thence over the conductor 102 to conductor 25 at station B, thence through brush 26, contact 27, brush 29, conductor 30, and thence through the winding of the magnet C at station B to earth or return conductor 15, causing such magnet C to be energized and thereby stepping around the step-by-step mechanism a further notch, just as if an additional train or car had entered the block from station B. At station A, the magnet C is not energized because, due to the energization of the magnet E, the circuit of the winding of the magnet C is opened at brushes 26 and 29. The car which has improperly entered the block from station A against the red signal in backing off causes the trolley wheel to first engage with trolley 180

switch contact 7, thereby allowing current to flow from the trolley wire 1, through conductor 16 to the relay armature 17, thence to contact 19 and by conductor 22 through the winding of the relay 11, energizing the same and causing the armature 19 to engage contact 13. And current also flows, however, through conductor 22 to conductor 24, and thence through the winding of the electro-magnet F at station A to earth or return conductor 15, causing the energization of the magnet F at station A with the consequent interruption of current in the signal wire 75, by withdrawal of contact 72 from between brushes 71 and 74. The interruption of the circuit through wire 75 causes at station B deenergization of the magnet D, with the result that the step-by-step mechanism is returned toward normal one notch; thus canceling the effect produced in that step-by-step mechanism when the car at station A improperly enters the block 1 against the red signal. Here again it is apparent that the improperly entering car in entering and backing out leaves the signals at the proper condition of indication.

In Fig. 3 a further modification of the circuit arrangement is shown which will, however, produce results similar to those described in connection with Figs. 1 and 2. Here the two extra signal wires 102 and 103 of Fig. 2 are supplanted by one extra signal wire 104 and a two-way switch. At each station an additional two-way switch is provided, and there is provided a second signal conductor connecting the two-way switches at the different stations. This two-way switch may take the form of the disk 49 with associated insulation 51, pin 50, brushes 52, 57, and 69, and may be operated by the same ratchet or notched wheel 46, as shown in Fig. 1. The two-way switch is shown as comprising the contact disk 49^a, mounted upon the shaft 45, with associated insulation 51^a, brushes 52^a, 57^a, and 69^a, the brush 52^a normally engaging the conducting pin 50^a. The brush 69^a at station A is connected by conductor 104 with brush 69^a at station B. Associated with the electro-magnet E at each station are the contact 99 and brushes 100 and 101, as in Fig. 2.

The counting in and counting out of trains or cars in the normal operation is the same as described in connection with Fig. 1. Suppose, however, that one or more cars or trains has or have entered the block 1 toward the left from station B. Then, the step-by-step mechanism at station B has been stepped around as many notches as cars or trains have entered the block, and at station B the white light and white semaphore are displayed, while at station A the red light and red semaphore are displayed, the electro-magnet E at station A being energized. So that bridging contact 27 has been with-

drawn from between brushes 26 and 29, while bridging contact 99 has been brought into engagement with brushes 100 and 101. Now suppose a car enters from the left toward the right from station A to block 1. The trolley wheel first engages contact 6 of the trolley switch with resultant flow of current from the trolley conductor 1 through conductor 25, thence through brush 100, contact 99, brush 101, conductor 105 to brush 52^a, to pin 50^a, to contact disk 49^a, to brush 69^a, thence over the signal conductor 104 to the distant station B, through brush 69^a, disk 49^a, to brush 57^a, (because the step-by-step mechanism has at station B removed the insulation 51^a from beneath the brush 57^a) to brush 26, through contact 27, to brush 29, conductor 30 through the winding of the magnet C at station B, thence to earth or return conductor 15, causing the energization of the magnet C at station B to count up on the step-by-step mechanism another notch, just as if an additional car or train had entered the block from station B.

When the car improperly entering from station A to the block backs out again, the contact 7 is first engaged by the trolley wheel, whereupon current will flow from the trolley conductor 1 through conductor 24, through the winding of the magnet F at station A to earth or return conductor 15, energizing said magnet F to remove the bridging contact 72 from between brushes 71 and 74, thus breaking the circuit through the signal wire 75 and causing at station B the deenergization of the magnet D, with the consequent return of the step-by-step mechanism one notch toward normal, thus canceling the effect of overcounting made by the improper entry of the car against the red at station A.

In Fig. 4, a further modification is shown, the semaphore switches of Fig. 1 being here again omitted and two signal wires extending between stations. Here the electro-magnets E at each station have associated with them, as in Figs. 2 and 3 the bridging contact 99 and the brushes 100 and 101. With the electro-magnet D at each station are associated two additional pairs of brushes and associated bridging contacts. Brushes 106 and 107 constitute one of these pairs and have associated with them the bridging contact 108. Brushes 109 and 110 constitute the other pair and have associated with them bridging contact 111. Normally, that is, when the magnet D is deenergized, brushes 109 and 110 are bridged by the contact 111, while the contact 108 is removed from between brushes 106 and 107. And when the magnet D is energized, brushes 106 and 107 are bridged while brushes 109 and 110 are insulated from each other. Brushes 107 and 110 are electrically connected together and by the signal wire 112, extending between

stations, are connected to the corresponding brushes 107 and 110 at the distant station. Brushes 26, 100, and 106 are electrically connected together and to conductor 25. And brushes 101 and 109 are connected together by conductor 113.

In the counting in and counting out of cars or trains the operation is substantially that described in connection with Fig. 1. Suppose, however, that one or more cars or trains has or have entered from station B toward the left to the block or section 1. Then the step-by-step mechanism at station B has counted up as many notches as cars or trains have entered the block and the white signals are displayed; and at station A the red signals are displayed, the electro-magnet E at station A being energized so that the circuit of electro-magnet C at station A is broken by the separation of contact 27 from brushes 26 and 29; but contact 99 has bridged the brushes 100 and 101. Now suppose a car improperly enters from turn-out A to block 1 against the red signals. In passing the trolley switch 6, 7, from left to right, current passes from conductor 1 through conductor 25, thence through brush 100, bridging contact 99, brush 101, conductor 113, brush 109, to brush 110, thence over the line signal wire 112 to the distant station where, since the magnet D at station B is energized, brushes 106 and 107 are bridged and current, therefore, flows from brush 106 to brush 26, by conductor 25, thence to brush 29, conductor 30, through the winding of the magnet C, to earth or return conductor 15, thus energizing the magnet C at station B and operating the step-by-step mechanism a further notch, just as if an additional car or train had entered the block 1 from turn-out B. Now, when the car backs out again from block 1 over the trolley switch 7, 6, at station A, current will flow over the conductor 24 through the winding of the electro-magnet F to earth or return conductor 15, energizing the electro-magnet F and causing the bridging contact 72 to be removed from between the brushes 71 and 74, thus interrupting the circuit through the signal wire 75 and causing a consequent deenergization of the magnet D at station B to move the step-by-step mechanism back toward normal one notch, thus canceling the effect of the improper entry from turn-out A to block 1 of the car or train running past the red signal.

In Fig. 5 a further modification is shown. Two signal wires are employed, one of them coöperating with white semaphore switches. When one or more cars or trains has or have entered the block section 1 toward the left from turn-out B, the step-by-step mechanism at that station has been stepped around a number of notches corresponding with the

number of cars or trains so entering the block, and the white light and white semaphore are displayed at station B, and at station A the red light and red semaphore are displayed, the electro-magnet E at station A being energized under these circumstances and, therefore, holding the bridging contact 27 away from brushes 26 and 29, so that the circuit of the magnet C at station A is open. But when the red semaphore is displayed at station A, due to the energization of magnet E, the contact 99 is bridging brushes 100 and 101. Conductor 25 at each station is connected also to a semaphore switch contact 114 while the opposing semaphore switch contact 115 is connected by conductor 116 with brush 101, the movable contacts or members of the white semaphore at both stations being connected by a signal wire 117 extending between stations. Now if a car runs past the read signal at station A to the block 1 from left toward the right, when the trolley wheel passes the trolley switch 6, 7, current will flow from trolley wire 1 through conductor 25, brush 100, bridging contact 99, brush 101, conductor 116 to white semaphore switch contact 115 at station A, and which is in contact with the movable member of the semaphore switch, since at station A the white semaphore 93 is in non-indicating position. Current then continues from contact 115 through a conductor 117 to the station B, thence to contact 114, since at that station the white semaphore is in indicating position and, therefore, the movable member of the semaphore switch is in engagement with the contact 114, thence from contact 114 over conductor 25 through brushes 26 and 29, conductor 30, through the winding of the electro-magnet C, conductor 31 to earth or other return conductor 15. In consequence, at station B the electro-magnet C is energized moving the step-by-step mechanism around another notch, just as if another train or car had passed from turn-out B from the block section 1 toward the left. In backing out again past the trolley switch 7, 6, at station A, current will flow from the trolley conductor 1 through conductor 24 to earth or return conductor 15, through the winding of the electro-magnet F, at station A, energizing said electro-magnet F so that the bridging contact 72 is removed from between brushes 71 and 74, thus breaking the circuit including the signal conductor 75, causing at station B the deenergization of the magnet D to return the step-by-step mechanism one notch, thus canceling the previously counted notch due to the improper entry of a car against the red from turn-out A to the block 1.

In Fig. 6, a further modification is shown where semaphore switches are omitted and two signal wires are employed. Here a

brush 118, connected to conductor 25, is adapted to be brought into electrical communication with the brush 119 by bridging contact 120 carried by the movable member of the electro-magnet D when that magnet is energized. Brush 119 is connected by conductor 121 with brush 122 normally in electrical communication with brush 123 by the bridging contact 124 carried by the movable member or armature of the electro-magnet C, the connection between brushes 122 and 123 being interrupted by withdrawal of the contact 124 when the electro-magnet C is energized. Brush 123 connects by conductor 125 with brush 101; and brushes 119 at the two stations are connected together by the signal wire 126, extending between stations.

The counting in and counting out operation is the same as in the preceding figures and in Fig. 1. Suppose one or more cars or trains has or have passed from turn-out B toward the left to the block section 1. Then at station B the step-by-step mechanism has been moved around a number of notches corresponding with the number of cars or trains which have so entered the block. At station B, therefore, the magnet D is energized and the brushes 118 and 119 are bridged by a contact 120 and the white signals are displayed. At station A, however, the electro-magnet E is energized so that the circuit of the winding of magnet C at station A is interrupted by withdrawal of contact 27 from between brushes 26 and 29; but brushes 100 and 101 are in electrical communication through bridging contact 99, and the red signals are also displayed. Magnets C and D are not energized under these circumstances at station A. Now, if a car or train improperly runs past the red at station A from the turn-out to the block section 1 toward the right, current will flow over conductor 25 to brush 100, thence across contact 99 to brush 101, thence by conductor 125 to brush 123, thence to brush 122 over contact 124, thence by conductor 121 to conductor 126 to the distant station B where current will flow through conductor 121, to brush 119, which, due to the energization of magnet D, is in electrical communication through contact 120 with brush 118, and current will flow by conductor 25 to brush 26, thence through contact 27 to brush 29, conductor 30, winding of the electro-magnet C, conductor 31, to earth or other return conductor 15. The electro-magnet C at station B is, in consequence, energized and moves the step-by-step mechanism around one more notch, just as if an additional train or car had passed from turn-out B toward the left to block section 1. Now when the car which improperly entered the block 1 from the left at station A backs out again, current will flow from

trolley conductor 1 through conductor 24 and the winding of the electro-magnet F to earth or return conductor 15, energizing the electro-magnet F so that bridging contact 72 is removed from between brushes 71 and 74, whereby the circuit of conductor 75, extending between stations, is interrupted, with the result that at station B the magnet D is deenergized temporarily, as in connection with the previous figures, whereby the step-by-step mechanism is returned one notch toward normal position, thus canceling at station B the notch or step counted up by the entry of the car or train past the red from turn-out A to block section 1.

From the description of Figs. 1 to 6 inclusive, it is apparent that a directional sensitive device is employed which operates to clear or set the signals according to the direction of the car or train; and it is also apparent that means are provided insuring that the signals, controlled by such directionally sensitive device, shall be left in the same condition after a car or train has run into the block against a red signal, and backed out again to wait, as before such car or train so improperly proceeded. And it is apparent from the description of the coöperation of the trolley switch contacts 6 and 7 and the relays 11 and 18, with conductors 24 and 25, that the construction, arrangement and operation is such that whichever of conductors 24, 25, is brought into electrical communication with the trolley wire 1 by initial engagement of trolley switch by the trolley wheel, remains so in electrical communication with the trolley conductor 1, the relays operating as transfer devices as the trolley wheel proceeds over the contacts to maintain the same relay energized throughout the passage of the trolley wheel over the contacts; and that when the trolley wheel passes in opposite direction the other of conductors 24 or 25 is brought into electrical communication with the trolley wire 1 and so remains during the passage of the trolley wheel over the contacts; and that though the trolley contacts 6 and 7 are separate, by the arrangement shown and described the length of time that the conductor 24, or 25, is in electrical communication with the trolley wire 1 is the same as if the contacts 6 and 7 were continuous.

What I claim is:

1. In a signaling system, home and distant stations at opposite ends of a block, car counting apparatus at said home station, a signal conductor extending between said stations, a stop signal at said distant station, a vehicle controlled contact and connections at said home station controlling the actuation of said counting apparatus and controlling the display of said stop signal through said conductor, a directionally sensitive switch at said distant station and con-

nections including another conductor extending between stations controlled by said switch for further actuation of said counting apparatus at said home station upon improper entry of a vehicle from said distant station to said block, clearing mechanism at said home station for returning said car counting apparatus toward normal, connections controlled by said directionally sensitive switch for actuating said clearing mechanism through said first mentioned conductor upon backing out of said vehicle from said block at said distant station, whereby the effect upon said car counting apparatus produced by said vehicle improperly entering said block at said distant station is canceled.

2. In a signaling system, home and distant stations at opposite ends of a block, car counting apparatus and a permissive signal at said home station, a stop signal at said distant station, a conductor extending between said stations, a vehicle controlled contact at said home station and connections controlling the display of said permissive signal and the actuation of said car counting apparatus and controlling the display of said stop signal through said conductor upon the passage of the first vehicle from said home station to said block, another conductor extending between said stations, a switch at each station in said second conductor, means actuating said switches when said permissive and stop signals are set, a directionally sensitive switch at said distant station, connections including said second conductor controlled by said directionally sensitive switch further actuating said car counting apparatus at said home station upon improper entry of a vehicle to said block at said distant station, and clearing mechanism at said home station for returning said car counting apparatus toward normal, said directionally sensitive switch controlling said clearing mechanism through said first named conductor upon backing out of said vehicle from said block at said distant station, whereby the effect upon said car counting apparatus upon improper entry of said vehicle at said distant station is canceled.

3. In a signaling system, home and distant stations at opposite ends of a block, car counting apparatus and means for actuating the same at both stations, a stop signal at said distant station, means controlling display of said stop signal at said distant station and controlling said means for actuating said car counting apparatus at said home station upon the passage of a vehicle from said home station to said block, means preventing operation of the means for actuating said car counting apparatus at said distant station when said car counting apparatus at said home station is actuated,

means at said distant station and coöperating means causing further actuation of said car counting apparatus at said home station upon improper entry of a vehicle from said distant station to said block, and means coöperating with said stop signal displaying means for restoring said car counting apparatus at said home station to its former condition upon the backing of said vehicle from said block at said distant station. 75

4. In a signaling system, home and distant stations at opposite ends of a block, signal displaying and clearing mechanism at said home station, a stop signal at said distant station, means for actuating said signal displaying mechanism at said home station and said stop signal at said distant station, said mechanism including car counting mechanism, car counting mechanism at the distant station, means preventing actuation of the car counting mechanism at said distant station when said signal displaying mechanism at said home station has been actuated, means at said distant station and coöperating connections causing actuation of said car counting mechanism at said home station upon improper entry of a vehicle from said distant station to said block, and means controlling said mechanism at said home station to return said car counting mechanism to its previous condition upon the backing out of said vehicle from said block at said distant station. 85

5. In a signaling system, home and distant stations at opposite ends of a block, step-by-step car counting mechanism at each station, an electro-magnet for actuating each of said car counting mechanisms, a clearing electromagnet at said home station controlling the return of said car counting mechanism at said home station toward normal, a stop signal at said distant station, a vehicle controlled switch contact at said home station and connections controlling said car counting magnet at said home station and said stop signal at said distant station, a switch interrupting the circuit of said car counting magnet at said distant station upon control of said car counting magnet at said home station by said vehicle controlled switch contact, means responsive to improper entry of a vehicle from said distant station to said block for controlling said car counting magnet at said home station, whereby said counting mechanism at 10 said home station counts another car, and means responsive to the backing out of said vehicle from said block controlling said clearing magnet at said home station to restore said car counting mechanism to its 11 previous condition. 11

6. In a signaling system, home and distant stations, car counting apparatus at both stations, a stop signal at a distant station, a conductor extending between said sta- 13

tions, a vehicle controlled contact and connections controlling said car counting apparatus at the home station and controlling said stop signal at said distant station through said conductor, means preventing actuation of car counting apparatus at said distant station upon actuation of said car counting apparatus at said home station, a second signal conductor extending between 10 said stations, and a directionally sensitive switch controlling one or another of said signal conductors depending upon the direction of movement of a vehicle, said second conductor connected with said controlling connections of said car counting apparatus at the home station and thereby controlling further actuation of said car counting apparatus at said home station.

7. In a signaling system, home and distant stations, car counting apparatus at both stations, a stop signal at a distant station, a conductor extending between said stations, a vehicle controlled contact and connections controlling car counting apparatus 20 at the home station and controlling said stop signal at said distant station through said conductor, means preventing actuation of said car counting apparatus at said distant station upon actuation of said car counting apparatus at said home station, a second signal conductor extending between said stations, a directionally sensitive switch controlling one or another of said signal conductors depending upon the direction of

movement of a vehicle, said second conductor connected with said controlling connections of said car counting apparatus at the home station and thereby controlling further actuation of said car counting apparatus at said home station, and a clearing magnet at said home station for returning said car counting apparatus toward normal, said directionally sensitive switch controlling said clearing magnet through said first named conductor to return said car counting apparatus to its previous condition.

10. In a signaling system, home and distant stations, step-by-step mechanism at each station, an electro-magnet controlling said step-by-step mechanism at each station, a permissive signal at said home station controlled by said electro-magnet at said home station, a stop signal at a distant station, an electro-magnet for controlling said stop signal, a vehicle controlled contact at said home station and connections controlling said electro-magnet at said home station and said stop signal magnet at said distant station, a switch in the circuit of the step-by-step magnet at said distant station controlled by said stop signal magnet at said distant station, a directionally sensitive switch at said distant station, and a conductor controlled by said directionally sensitive switch connected with said controlling connections of said electro-magnet at said home station and connected to said switch controlling said step-by-step magnet at said distant station.

11. In a signaling system, home and distant stations, permissive and stop signals at each station, car counting mechanism at each station, a vehicle controlled switch and connections controlling said car counting mechanism at said home station and controlling the stop signal at said distant station, a switch at said distant station preventing actuation of the car counting apparatus thereat when said stop signal thereat is displayed, a conductor connected to said last named switch and connected with said controlling connections of said car counting apparatus at said home station, and a directionally sensitive switch at said distant station controlling said conductor.

12. In a signaling system, home and distant stations, permissive and stop signals at each station, car counting mechanism at each station, a vehicle controlled switch and con-

13. In a signaling system, home and distant stations, permissive and stop signals at each station, a directionally sensitive switch at each station, a conductor extending between stations and connections controlling the display of the permissive signal at said home station and said stop signal at said distant station, a second conductor, extending between said stations, a switch controlled by each permissive and each stop signal at each station included in said conductor, said switches at each station being connected in multiple with each other, step-by-step mechanism at said home station, and connections including said second conductor controlled by said directionally sensitive switch at said distant station for actuating said step-by-step mechanism.

14. In a signaling system, home and distant stations, permissive and stop signals at each station, a directionally sensitive switch at each station, a conductor extending between stations and connections controlling the display of the permissive signal at said home station and said stop signal at said distant station, a second conductor, extending between said stations, a switch controlled by each permissive and each stop signal at each station included in said conductor, said switches at each station being connected in multiple with each other, step-by-step mechanism at said home station, and connections including said second conductor controlled by said directionally sensitive switch at said distant station for actuating said step-by-step mechanism.

- connection controlling said car counting mechanism at said home station and controlling the stop signal at said distant station, a switch at said distant station preventing actuation of the car counting apparatus thereat when said stop signal thereat is displayed, a conductor connected to said last named switch and connected with said controlling connections of said car counting apparatus

5 at said home station, a directionally sensitive switch at said distant station controlling said conductor, and switches in said conductor extending between said stations, and means for controlling one of said last named

10 switches at each station upon the display of a signal at each station.

11 13. In a signaling system, home and distant stations, car counting mechanism at each station, a car counting magnet at each

20 station, a stop signal at a distant station, a vehicle controlled contact, a conductor extending between stations, said vehicle controlled contact and connections controlling said car counting magnet at the home station and controlling said stop signal at said distant station through said conductor extending between stations, means preventing actuation of said car counting magnet at said distant station upon actuation of said

25 car counting magnet at said home station, a second signal conductor extending between said stations, a restoring electro-magnet at each station controlling restoration of the car counting mechanism thereat, and a directionally sensitive switch for controlling either said car counting magnet or said restoring magnet at a station depending upon the direction of movement of a vehicle, said second conductor connected with said controlling connections of said car counting mechanism at said home station and thereby controlling further actuation of said car counting mechanism at said home station.

30 14. In a signaling system, home and distant stations, a signal and a controlling magnet therefor at said home station, vehicle controlled means controlling said magnet, a stop signal and a controlling magnet therefor at the distant station, means for displaying said stop signal upon the display of said signal at said home station comprising a circuit including said magnets in series with each other, and a vehicle controlled switch at said distant station and connections causing oversetting of said controlling means at said home station upon improper passage of said stop signal by a vehicle at said distant station.

35 15. In a signaling system, home and distant stations, a signal and a controlling magnet therefor at said home station, vehicle controlled means controlling said magnet, a stop signal and a controlling magnet therefor at the distant station, means for displaying said stop signal upon the display

40 of said signal at said home station comprising a circuit including said magnets in series with each other, a vehicle controlled switch at said distant station and connections causing oversetting of said controlling means at said home station upon improper passage of said stop signal by a vehicle at said distant station, said vehicle controlled switch at said distant station and connections causing return of said controlling means at said home station to its previous condition upon return of said vehicle past said stop signal.

45 16. In a signaling system, home and distant stations, a signal at said home station, vehicle controlled means controlling said signal, a stop signal at said distant station, a circuit extending between said stations energized upon the display of said signal at said home station, said circuit when energized maintaining said signals at said home and said distant stations at display positions, a second circuit extending between said stations, said circuit when energized oversetting said signal controlling means at said home station, and a vehicle controlled switch controlling said second circuit to energize the same upon passage of a vehicle past said stop signal at said distant station.

50 17. In a signaling system, home and distant stations, a signal at said home station, vehicle controlled means controlling said signal, a stop signal at said distant station, a circuit extending between said stations energized upon the display of said signal at said home station, said circuit when energized maintaining said signals at said home and said distant stations at display positions, a second circuit extending between said stations, said circuit when energized oversetting said signal controlling means at said home station, and a vehicle controlled switch controlling said second circuit to energize the same upon passage of a vehicle past said stop signal at said distant station, said vehicle controlled switch controlling said first circuit to deenergize the same upon return of said vehicle past said stop signal at said distant station, and means controlled by the deenergization of said first circuit whereby said signal controlling means at said home station is returned to its previous condition.

55 18. In a signaling system, home and distant stations, a signal at said home station, vehicle controlled means controlling said signal, a stop signal at said distant station, a circuit extending between said stations energized upon the display of said signal at said home station, said circuit when energized maintaining said signals at said home and said distant stations at display positions, a second circuit extending between said stations, said circuit when energized oversetting said signal controlling means at said home station, and a vehicle controlled switch controlling said second circuit to energize the same upon passage of a vehicle past said stop signal at said distant station, said vehicle controlled switch controlling said first circuit to deenergize the same upon return of said vehicle past said stop signal at said distant station, and means controlled by the deenergization of said first circuit whereby said signal controlling means at said home station is returned to its previous condition.

60 19. In a signaling system, home and distant stations, a signal and a controlling magnet therefor at said home station, vehicle controlled means controlling said magnet, a stop signal and a controlling magnet therefor at the distant station, means for displaying said stop signal upon the display

65 of said signal at said home station comprising a circuit including said magnets in series with each other, a vehicle controlled switch at said distant station and connections causing oversetting of said controlling means at said home station upon improper passage of said stop signal by a vehicle at said distant station, said vehicle controlled switch at said distant station and connections causing return of said controlling means at said home station to its previous condition upon return of said vehicle past said stop signal.

trolled switch controlling said second circuit to energize the same upon passage of a vehicle past said stop signal at said distant station, and switches in said second circuit 5 at the home and distant stations closed upon energization of said first circuit.

19. In a signaling system, home and distant stations, a signal at said home station, vehicle controlled means controlling said 10 signal, a stop signal at said distant station, a circuit extending between said stations energized upon the display of said signal at said home station, said circuit when energized maintaining said signals at said home 15 and said distant stations at display positions, a second circuit extending between said stations, said circuit when energized oversetting said signal controlling means at said home station, a vehicle controlled

switch controlling said second circuit to energize the same upon passage of a vehicle past said stop signal at said distant station and controlling said first circuit to deenergize the same upon return of said vehicle past said stop signal at said distant station, 20 means controlled by the deenergization of said first circuit to return said signal controlling means at said home station to its previous condition, and switches in said second circuit at the home and distant stations 25 closed upon energization of said first circuit.

In testimony whereof I have hereunto affixed my signature in the presence of two subscribing witnesses.

CARL P. NACHOD.
